UNITED STATES PATENT OFFICE.

GIDEON G. COOK, OF HUMBOLDT, IOWA.

AUTOMATIC CORD OR TWINE ELEVATOR OR HOLDER.

SPECIFICATION forming part of Letters Patent No. 272,211, dated February 13, 1883.

Application filed December 5, 1882. (No model.)

To all whom it may concern:

Be it known that I, GIDEON G. COOK, of Humboldt, in the county of Humboldt and State of Iowa, have invented certain new and useful Improvements in Automatic Cord or Twine Elevators or Holders; and I do hereby declare the following to be a full, clear, and exact description of the invention, such as will enable others skilled in the art to which it pertains to make and use it, reference being had to the accompanying drawing, which forms part of this specification.

My invention relates to an improvement in automatic cord or twine elevators or holders; and it consists in the combination of a bracket, which forms a support both for the cord-holder and the spring-actuated arm, through the outer end of which the cord passes, as will be more fully described hereinafter.

20 The object of my invention is to provide a cheap and simple cord-holder which will instantly raise the end of the cord up high enough to be out of the way after its end has been broken off in tying up a bundle.

25 The accompanying drawing represents a cord or twine holder which embodies my invention.

A represents a suitable wire bracket, which is to be secured to the ceiling in any suitable manner, and which has an eye, C, formed in it 30 at any distance below the ceiling. The lower end of this bracket is curved downward and outward, and has an eye, D, formed in its lower end. From this eye D is suspended a suitable cord-holder, E, of any kind that may be preferred. The arm F, which has its inner end,

G, bent inward upon itself, is hung or supported in the eye D on the bracket, and has its shorter end G connected with the eye C, formed in the bracket, by means of the spring O. This spring serves to keep the outer end of the arm F pressed upward, and to cause it to spring back into position as soon as the spring is released. In the outer end of the arm F is formed a guiding-eye, J, through which the string from the ball is passed. When the string is taken 45 hold of for the purpose of tying up a bundle the pull upon the string is just sufficient to depress the outer end of the arm F, so that when the string is released, after its end has been broken off, the arm will spring upward 50 and raise the lower end of the string just high enough above the counter to have it conveniently taken hold of, and yet out of the way.

It will be seen that this cord or twine holder can be made of spring-wire, that the parts are 55 very few and simple, and that it is almost impossible for them to get out of order.

Having thus described my invention, I claim—

An automatic cord or twine elevator consisting 60 of the bracket A, having suitable eyes formed in it, the arm F G, a spring, and a cord-holder, the parts being combined and arranged to operate substantially as shown and described.

In testimony whereof I affix my signature in 65 presence of two witnesses.

GIDEON G. COOK,

Witnesses:
R. C. TUNISON,
C. A. BABCOCK.
